UNITED STATES PATENT OFFICE.

LESTER R. WELLMAN, OF CHICAGO, ILLINOIS, ASSIGNOR TO FRIELEY VOSHARDT CO.,
OF CHICAGO, ILLINOIS, A CORPORATION OF ILLINOIS.

DESIGN FOR A PLATE FOR LIGHTING FIXTURES.

Application filed March 31, 1922. Serial No. 1,467. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Plate for Lighting Fixtures, of which the following is the specification, reference being had to the accompanying drawing, forming part thereof.

Fig. 1 is a semi-sectional surface view of a plate for lighting fixtures, showing my new design.

Fig. 2 is a side elevation of the same.

I claim:

The ornamental design for a plate for lighting fixtures, as shown.

LESTER R. WELLMAN.
